(57) **CLAIM**

The ornamental design for an intervertebral fusion implant, as shown and described herein.

DESCRIPTION

This application claims priority to the U.S. patent application Ser. No. 12/202,690 filed Sep. 2, 2008, the entire contents of which are incorporated herein by reference.

FIG. 1 is a perspective view of an intervertebral fusion implant showing our new design;

FIG. 2 is a top plan view thereof;

FIG. 3 is a bottom plan view thereof;

FIG. 4 is a front elevation thereof;

FIG. 5 is a rear elevation thereof;

FIG. 6 is a side elevation thereof; and,

FIG. 7 is a side elevation of the side opposite that shown in FIG. 6.
